JOHN GREGSON, OF FALL RIVER, MASSACHUSETTS.

APPARATUS FOR TREATING YARN.

SPECIFICATION forming part of Letters Patent No. 622,001, dated March 28, 1899.

Application filed April 26, 1898. Serial No. 678,828. (No model.)

To all whom it may concern:

Be it known that I, JOHN GREGSON, of Fall River, in the county of Bristol and State of Massachusetts, have invented a new and useful Improvement in Apparatus for Treating Yarn; and I hereby declare that the following is a full, clear, and exact description of the same, reference being had to the accompanying drawings, forming part of this specification.

This invention has reference to an organized apparatus for treating yarn on the cop or bobbin for use in the loom.

The object of the invention is to prepare filling-yarn, and particularly filling-yarn spun on ring-spinning frames, for use in the shuttles of the looms expeditiously and without injuring the bobbins; and to this end the invention consists in a suitable receptacle in which the filling-yarn is placed while on the bobbin or cop and mechanism by which air charged with water is drawn through the filling, whereby the twist in the yarn is set and kinks in the yarn avoided.

Filling-yarn spun on ring-spinning machines is wound on bobbins usually made of wood and varnished. The yarn in the process of spinning is twisted and laid spirally on the bobbins. When the yarn is now drawn off the bobbins, any slackness in the same will cause it to kink. Mule-yarn being spun either on the bare spindle or on paper quills is usually steamed, which causes the twist to set; but bobbins when subjected to steam are liable to alter in shape and the varnish on the same soften, so that the yarn will stick to the bobbins, and as filling-bobbins are built up in conical layers—one or two rings of each conical layer in contact with the varnish on the bobbin—they will become cemented to the bobbin and the yarn on the same is liable to break at each conical layer, making such bobbins unfit for use in the shuttle on account of the frequent breaks in the filling.

In my apparatus a forced current of air is made to pass through sprays of finely-divided streams of water, forming a mist, in which the rapidly-moving air carries the atomized water onto, around, and between the filling-

yarn on the bobbins, by which the water mechanically carried by the air is absorbed and the air is drawn from the upper part of the receptacle to be forced again through the sprays of water and through the mass of bobbins containing the filling-yarn. By the use of this apparatus the filling-yarn can be thoroughly moistened in a very short time without injuring the bobbins or affecting the varnish on the same. New bobbins may be continuously added and the moistened bobbins withdrawn, or the apparatus may be used to dampen the filling on a batch of bobbins and then by stopping the flow of the water partly dry the bobbins by forcing the air under normal conditions through the chamber containing the bobbins.

Figure 1 is a front view, partly in section, of my apparatus. Fig. 2 is a vertical longitudinal section of the same.

In the drawings I have shown the apparatus in connection with the floors above and below the chamber into which the bobbins are placed, this being the construction I have used and which illustrates the best practical application I have so far made of the invention. I do not, however, wish to confine myself to the exact relation of the apparatus to the floors or to the exact relation of the various parts to each other, as they may be altered and arranged to best adapt the apparatus to the existing conditions and the convenience of the user.

In the drawings, A indicates the floor on which the apparatus is supported; B, the upper floor; C, a chamber, the four sides, the top, and the bottom of which may be made of seasoned wood or other material, (the chamber should be practically air-tight;) D, a trunk extending from the chamber C upward above the floor B and provided with the cover d, preferably hinged at one side to the trunk; E, an inclined grating, and F the doors, preferably arranged to slide on vertical ways and connected with the counterbalance-weight f by a chain or cord passing over a pulley. The chamber C is preferably provided with the inclined deflector e. The bobbins containing the filling-yarn are thrown into the chamber C through the trunk D and are supported on

the grating E, which is sufficiently inclined to cause the filled bobbins to slide and roll on the grating toward the doors F.

In practice the chamber is filled with the 5 filling-bobbins at or nearly to the point where the deflector c projects from the vertical wall forming the front of the chamber.

The pipe G is a pipe connected with a water-supply under pressure. It is provided with 10 a valve G', by which the water-supply is controlled. The lower end of the pipe G connects with a pipe extending across the chamber under the higher end of the grating E. From this transverse pipe a series of pipes 15 G² extend longitudinally and are each provided with a series of atomizers G³ G⁴, consisting, as shown in Fig. 2, of a nozzle and a deflector supported in front of the nozzle, by which the water ejected under pressure from 20 the nozzle is broken up and distributed, forming a mass of spray under the grating E. The lower part of the chamber is lined with tin or other waterproof material and is provided with the drain-pipe G⁴, by which the 25 surface water is carried off. The water-atomizing apparatus just described is one of several well-known means for subdividing the water into a spray, and any other well-known device adapted to form a continuous spray 30 under the grating or supply the air in the part of the chamber under the grating E with water spray may be used in lieu of the apparatus described.

The pipe H, connected with the upper part 35 of the chamber C, extends downward and connects with the blower H' and from the blower with the lower part of the chamber C below the grating E. The blower H' may be a fan-blower or a pressure-blower. When a considerable depth of filling-bobbins is to be 40 treated at one time, a pressure-blower is preferred. The blower is driven by a belt connecting the pulley on the blower with the driving-pulley H², which is driven from some 45 convenient shaft or prime motor.

When it is desired to complete the treatment of the filling in the apparatus by circulating air through the mass of filling-bobbins after they have been thoroughly dampened 50 or it is desired to increase the capacity of the air to carry the water sprayed into the lower part of the chamber through the mass of filling-bobbins, the chamber h, provided with a coil of steam-pipes, as indicated in Fig. 1, 55 may be placed at any convenient part of the pipe H, so that the air in passing through the chamber h may be slightly heated and the capacity of the air to absorb and to carry moisture increased.

60 The operation of the apparatus is as follows: When the chamber C has been partly filled with filling-bobbins to a point above the openings for the doors F and preferably to a point above the lower edge of the deflector c, 65 the water may be let onto the spraying devices and the blower H' started. As the

blower draws the air from the upper part of the chamber C a partial vacuum is produced in the part of the chamber above the mass of filling-bobbins, and as the blower forces the 70 air into the lower part of the chamber C below the grating E a plenum exists in this part of the chamber, and the air, passing through the sprayed water, carries the water through the grating onto, between, and through the 75 mass of filling-bobbins, depositing the moisture of the filling-yarn. The lower portion of the mass of bobbins is the first to be thoroughly dampened. By opening the doors F 80 the lower bobbins may be removed from the chamber from time to time and more filling-bobbins added to maintain a considerable depth of bobbins.

The deflector portion c facilitates the withdrawing of the lower portion of the mass of 85 bobbins, as it prevents the descent of the upper mass of bobbins at the front near the doors.

All the filling on the bobbins in the chamber may be sufficiently dampened in a short 90 time by running the blower at a high speed, so as to produce a rapid circulation of the air and a partial lifting of the bobbins by the greater air-pressure below than above the bobbin mass, and after operating the spray- 95 devices for a sufficient time and then shutting off the water-supply the rapid upward circulation of the air will carry any excess of moisture from the lower bobbins and distribute the same equally through the mass of 100 bobbins. A slight heating of the air in its passage through the chamber h will facilitate the process; but the air must not be heated so as to affect the bobbins or the varnish on the same.

Filling-yarn treated as above described has the twists perfectly set and does not kink when slack, as does the untreated filling. It is therefore better adapted for use in the loom-shuttle.

Having thus described my invention, I claim as new and desire to secure by Letters Patent—

1. In an apparatus of the nature herein described for treating filling, the combination of 115 the following instrumentalities: a chamber having an inlet-opening and the top, an inclined grid, or grating, for the support of the filling, a water-spraying device under the grid, or grating, a blower connected with the 120 upper and the lower part of the chamber, and a door for the discharge of the filling; whereby the filling may be dampened, as described.

2. In an apparatus for treating yarn, the combination with an inclosed chamber having 125 an upper inlet-opening, a discharge-opening closed by a door, and an inclined grating for the support of the yarn, of a water-spraying device under the grating, a pipe having a valve for regulating the water-supply, a 130 blower, a pipe connecting the blower with the upper part of the chamber and the space un-

- der the grating, actuating mechanism connected with the blower, and a drip-pipe for carrying off the surplus water; whereby the air exhausted from the upper part of the 5 chamber is forced through the spray of water and through the mass of yarn on the grating, and the yarn is dampened, as described.
3. In an apparatus for treating yarn, a chamber having inlet and outlet openings, a 10 grating for supporting the yarn, a water-spraying device, and mechanism, substantially as described, whereby currents of moistened air are forced through the yarn in the chamber, as described.
- 15 4. In an apparatus for treating yarn, the combination with a chamber having inlet and outlet openings, a grating for supporting the yarn, a blower connected with the top and bottom of the chamber, of a water-spraying 20 device for charging the incoming air with water, and a chamber having a coil of steam-

pipes; whereby the air may be heated to increase its capacity for holding moisture, as described.

5. In an apparatus for treating yarn, the 25 combination with a chamber having inlet and outlet openings, a grating for the support of the yarn, of the inclined deflector c, the spraying devices G³ G³, the water-supply pipe G, the controlling-valve G', the blower H', the 30 pipe H connecting the upper and lower part of the chamber with the blower, and mechanism for operating the blower, whereby the sprayed water is carried by the forcibly-circulating air onto the yarn to dampen the 35 same, as described.

In witness whereof I have hereunto set my hand.

JOHN GREGSON.
